[57] CLAIM

The ornamental design for a vintners' bin and cabinet, substantially as shown and described.

DESCRIPTION

FIG. 1 is a front elevation view of a vintners' bin and cabinet showing our design.

FIG. 2 is an elevation of one side thereof.

FIG. 3 is top plan view thereof.

FIG. 4 is a front perspective view thereof.

The other side of the vintners' bin and cabinet is the same as in FIG. 2 in reverse.

The rear elevation and bottom plan view are plain and the same respectively as in FIGS. 1 and 3 in outline.

The broken lines in the figures are for illustration purposes only.

Fig. 3.
